UNITED STATES PATENT OFFICE.

CHARLES MEISTER, OF PHILADELPHIA, PENNSYLVANIA.

PORTABLE MUSIC-STAND.

SPECIFICATION forming part of Letters Patent No. 634,533, dated October 10, 1899.

Application filed January 30, 1899. Serial No. 703,817. (No model.)

To all whom it may concern:

Be it known that I, CHARLES MEISTER, a citizen of the United States, residing at Philadelphia, in the county of Philadelphia and State of Pennsylvania, have invented a new and useful Portable Music-Stand, of which the following is a specification.

My invention relates to improvements in portable music-stands.

10 The object of my invention is to afford a convenient stand for the support of sheet-music and which when not in use is adapted to be folded into a compact form for convenient transportation.

15 Referring to the drawings, Figure 1 is a perspective view of my device opened and ready for use. Fig. 2 is a view of the same closed and ready for transportation, the cylinder being in longitudinal section; also, piece 20 7 is in section, with one of the legs 15 removed. Fig. 3 is a cross-section on the lines $\alpha\alpha$ of Fig. 1. Fig. 4 is a detailed view of the upper part of member 10, with 14 and 11 in section. Fig. 5 is a detailed view in section, showing 25 spring means for deflecting the leg when projecting from the cylinder.

Similar numerals refer to similar parts throughout the various views.

The cylinder 1 is provided with the diametrically opposite longitudinal slots 2 and 3. Within the cylinder are located the supporting members 6 and 7, each provided with a threaded stud projecting through slots 2 and 3, respectively, and carrying thereon the knurled nuts 8 and 9, respectively. The said nuts are located outside the cylinder and are adapted for the manual operation and adjustment of their respective supporting members 6 and 7. Attached to the supporting member 6 is the rod 10, which extends longitudinally through the center of the cylinder and is curved slightly at its outward end. Adjustably secured to rod 10 by the loop 11 is the member 14, which forms part of and supports the other members of the collapsible rack. This rack consists of the horizontal pieces pivoted at the upper and lower ends of member 14 and having their outward ends pivotally connected with the pieces parallel 45 to member 14, so that when the lower horizontal members are moved upwardly to lie parallel with each other and with member 14

the other members also lie together, as shown in Fig. 2. Secured to the member 14 is a spring 13, which projects through a slot in 55 said member 14 and engages with the rod 10, normally to hold the piece 14 in any required position on member 10.

Upon opening the stand member 6 is released from the position shown in Fig. 2 by 60 loosening the knurled nut 8. It is then raised to the position shown in Fig. 1 and there secured by tightening the said nut 8. The collapsible rack and the member 14, to which it is secured, are then drawn upward upon the 65 member 10 to the position shown in Fig. 1 and held there by spring 13 at the desired inclination.

Pivotedly secured to member 7 are the legs 15, which, when the device is in the condition 70 shown in Fig. 2, lie folded in a parallel position within the cylinder and extend approximately throughout the length thereof.

Upon releasing supporting member 7 from the position shown in Fig. 2 by loosening the 75 knurled nut 9 the said member 7 may be moved to the position shown in Fig. 1 and there secured again by tightening the knurled nut 9. When the supporting member 7 reaches the position shown in Fig. 1, the legs 15 have 80 become sufficiently released from the cylinder to respond to the action of springs 16 to spread in the position shown in said Fig. 1. The grooves 17 in the base of said cylinder, which are occupied by the legs when extended, 85 serve to hold said legs in their proper respective radiating positions. The springs 16 are secured to said legs near their pivoted end and are adapted to abut against projections 18 on the supporting member 7. 90

It will be noted that the leg-supporting member is horseshoe-shaped, and the rack-supporting member is of a corresponding shape to occupy the space inclosed by said leg-supporting member, so that one member 95 will readily slide past the other without interference. By constructing the rack so as to slide upon the supporting-rod 10 when the rack is folded it will lie alongside the rod 10 and each extend approximately the entire 100 length of the cylinder and surrounded by the three legs, as above described. By this construction it will be noted that I have provided a device capable of extension to about three

times the length of the cylinder—that is, I have provided a music-stand readily extended to the normal height for such devices and readily folded and which when folded for transportation assumes the proportions of an ordinary music-roll.

5. What I claim is—

1. In a portable music-stand, a music-rack, a supporting member therefor bent at its upper extension, and spring means connected with the rack for adjustably securing the rack in the desired position upon said supporting member, substantially as described.

10. 2. In a portable music-stand the combination of a hollow casing, a rack-supporting member and a leg-supporting member adapted to slide within the casing, from end to end, each past the other, and means for manually operating and adjustably securing each, substantially as described.

15. 3. In a portable music-stand the combination of a hollow casing, a folding rack and a standard therefor, and folding legs, each when within the casing occupying positions side

20. by side, and each extending approximately 25 the length of the casing, with manually-operative means for moving said rack-standard and legs respectively, and for adjustably securing the same, substantially as described.

4. In a portable music-stand the combination of a hollow casing having diametrically opposite longitudinal slots, supporting members adapted to slide longitudinally within the casing and provided with external means for manual operation connected with the same 30 through the opposite slots respectively and means for adjustably securing said supporting members in any desired position; legs connected with one supporting member, spring-actuated and adapted to spread when sufficiently extended from the cylinder, and a folding rack and support therefor connected with the other supporting member, substantially as described.

35. CHAS. MEISTER.
